HAND SUPPORTED REAR VIEW MIRROR

Jean-Paul Galarneau, 1438 Marie Victorin,
St. Nicholes, Quebec, Canada

Filed Nov. 5, 1970, Ser. No. 26,425

Claims priority, application Canada Sept. 4, 1970

Term of patent 14 years

Int. Cl. D3—99

U.S. Cl. D86—10

FIG. 1 is a top plan view of a hand supported rear view mirror showing my new design;

FIG. 2 is a bottom plan view thereof.

FIG. 3 is an end elevation taken from the left of FIG. 1.

FIG. 4 is a front elevation.

FIG. 5 is an end elevation taken from the right of FIG. 1.

FIG. 6 is a rear elevation.

FIG. 7 is a bottom perspective at a reduced scale.

I claim:

The ornamental design for a hand supported rear view mirror, as shown.
